UNITED STATES PATENT OFFICE.

LOUIS ELMER GAUME, OF AKRON, OHIO.

GARMENT HANGER.

Application filed October 12, 1925. Serial No. 61,915.

This invention relates to new and novel improvements in garment hangers and while it may be used to advantage generally, it is particularly intended for dry cleaners and 5 tailors for securing trousers to a garment hanger.

One object of the invention is to provide new and useful means for protecting the garment from rust, dust or other matter 10 which may accumulate on the supporting bar of the garment hanger.

Another object is to provide simple, efficient means whereby a garment will be engaged and held in position on a hanger.

15 A further object is to provide a new and useful card which may be manufactured at a low cost and which may be quickly and conveniently attached to a garment hanger and to a garment, positioned thereon, to 20 provide a prominently presented surface for the name of the merchant or dry cleaner or other advertising matter.

The above and additional objects are accomplished by the novel construction, combination and arrangement of parts herein-after described and illustrated in the accompanying drawing, wherein I have shown a preferred form of the invention, it being understood that the invention is capable 30 of various adaptations and that changes and modifications may be made or resort had to substitutions which come within the scope of the appended claims.

In the drawings like characters of reference are employed to denote like parts as 35 the same may appear in any of the several views and in which:—

Figure 1 is a plan view of a device constructed in accordance with this invention.

40 Figure 2 is a perspective view of same showing the manner in which it is folded to position it on a hanger.

Figure 3 is a front elevational view of a hanger showing a device constructed in 45 accordance with this invention attached thereto and also showing a pair of trousers operatively positioned thereon.

Figure 4 is a sectional view taken as indicated by the line 4—4 of Figure 3.

50 Proceeding now to a detailed description of the invention with reference to the accompanying drawing, the numeral 5 denotes a garment hanger provided with a supporting bar 6. The numeral 7 denotes a sheet 55 or card board or other suitable material which is preferably rectangular in form and

is provided with two spaced parallel slits 8 and 9. The slit 8 is provided at each end thereof with downwardly inclined extensions 8^a and 8^b and the slit 9 is likewise provided at each end thereof with upwardly inclined extensions 9^a and 9^b; each of said extensions terminating in spaced relation to the edge of the sheet 7, thereby forming a strip 10 which is connected to the sheet 7 at each end thereof. The sheet is folded as indicated by the dotted line 12 to form the portion 11, and provide a hook adapted to receive the supporting bar 6.

In use, the card 7 is folded as shown in Figure 2 and the portion 11 is positioned over the bar 6 as shown in Figure 3. The portion 11 may then be secured to the main portion of the card 7 by means of the spring clips 13 or other suitable means. To position a pair of trousers 14 on the hanger, the legs of the trousers are entered in the slot 9 and pulled under the strip 10 and out through the slot 8 and drawn downwardly to the position shown in Figure 3. As the sheet 7 is composed of relatively stiff material, the strip 10 will bend outwardly as shown in Figure 4, leaving the legs of the trousers depending in a straight line. The strip 10 engages the legs of the trousers and holds the same against accidental removal from the hanger. The upturned ends 9^a and 9^b and 8^a and 8^b of the slots 8 and 9 permit the material adjacent the strip 10 to be easily bent inwardly, thereby facilitating the operation of positioning the trousers through said slots.

It will thus be seen that with the trousers operatively positioned thereon, that the strip 10 will be prominently displayed and that 95 the name of the cleaner or other advertising matter may be printed thereon.

Having thus illustrated my invention, and described the same in detail, what I claim as new and desire to secure by Letters Patent is:—

1. In combination, a garment hanger having a horizontal bar, a sheet of relatively thin material folded to provide a front portion and a back portion, said sheet positioned on said bar with the bar received in said fold, the front portion being provided with longitudinally directed parallel slots to provide a band substantially as and for the purpose set forth.

2. In a device of the class described, a piece of sheet material folded upon itself,

a band on the forwardly presented fold, said band formed by two parallel horizontal slots, each disposed in parallel relation to the line of said fold.

5. In a device of the class described, a piece of sheet material bent upon itself to provide a rear portion and a relatively wider front portion, a band in said forward portion, said band extending in parallel relation to the line of fold and being formed by two cuts in said forward portion.

6. In a device for holding a pair of trousers on a garment hanger, a flat piece of sheet material adapted to be folded along

10 a certain line to position it over the supporting bar of the garment hanger, said sheet material having a band formed by

cuts, arranged in parallel spaced relation to the line of fold, each cut terminating in spaced relation to each edge of said material, 20 said cuts adapted to receive the leg portion of a pair of trousers.

5. In a device for holding a pair of trousers on a garment hanger, a piece of sheet material adapted to be folded upon itself to receive the supporting bar of the hanger, a band on the forward portion of said material, said band being formed by two cuts in said material, said cuts terminating at each end thereof in oppositely inclined extensions.

30 In testimony whereof I have hereunto set my hand:

E. ELMER GAUME.
